UNITED STATES PATENT OFFICE

ELMER B. BECK, OF LITITZ, PENNSYLVANIA

CONVERTIBLE STOOL STEPS

Application filed August 23, 1929. Serial No. 387,835.

This invention relates to convertible furniture and more particularly to a combination stool and short step-ladder for use in kitchens, libraries and similar places where reference is had to books, wares, or the like, and it is desirable such works of reference or wares be promptly replaced.

The primary object of this invention is to provide an article of the typified character which is readily converted, by a slight pedal movement, from one position of use to the other.

Other objects are to provide a properly-balanced convertible stool-steps which is sturdy in construction, attractive in appearance, comprises but few parts, and that fully justifies all the aims and advantages for which it is designed.

With the foregoing objects in view and which will better appear as this description proceeds, my invention resides in the combination and arrangement of parts, as well as certain details of construction hereinafter set forth and claimed; it being understood that changes in the precise embodiment, herein disclosed, may be made within the scope of what is claimed, without departure from the essential features of said invention.

In the drawing:

Fig. I is a perspective view of my novel convertibly-balanced stool-steps in the collapsed position for use as a stool or bench.

Fig. II is a perspective view showing my improved stool-steps opened up or "tumbled" into position for use as a steps or ladder.

Fig. III is a sectional view illustrative of the manner in which the stool-steps of my invention is readily converted from one position of use to the other by a slight pedal movement without disturbing its proper balance.

Fig. IV is a perspective view of the main or rigid component of the improved convertible stool-steps.

Fig. V is a perspective view of the movable or balanced component; and,

Fig. VI is a perspective view of a cross-bar or pivot member, hereinafter fully explained.

Referring more in detail to the illustrations my novel combination stool and step

ladder consists of three main parts, namely; a rigid component structure or stool comprehensively designated 1, a movable balanced component structure or steps similarly characterized 2, and a cross-member or pivot component likewise marked 3—Fig. VI.

The stool or stationary component 1 comprises a top 4 supported on front and back legs 5, 6 respectively, rigidly braced together by appropriate horizontals 7, while corner struts 8 are fitted, where they do not interfere with the movements of the steps 2, to ensure added rigidity.

The movable balanced component 2 comprises parallel side members or "horses" 9 of 65 rocker-like configuration, suitably shaped to provide risers 10 for the steps 11; and said horses are firmly braced at the back by a stretcher-bar or actuator 12, in advance of which I provide aligned holes 13—Fig. V, for 70 a purpose later on explained.

The cross member or pivot component 3 conveniently consists of a long bolt or rod, headed at one end 14, and screw threaded at the other end to receive a lock nut or nuts 15; 75 with a plurality of spacer sleeves or washers 16.

Having outlined the main structural features of the respective components 1, 2 and 3, I will now explain their assembly; it being 80 firstly noted that the over-all width of the balanced steps 2 is of a dimension sufficiently less than that between the stool front legs 5, to freely accommodate the spacer sleeves or washers 16: while said front legs are suitably 85 bored at 17—Fig. IV—to snugly receive the pivot component 3.

The steps 11 and stool top 4 may be finished with suitable treads 18 of appropriate character, while the rear lower horizontal 7' is 90 fitted with one or more buffer stops 19 capable of compression to absorb impacts, when the steps 2 are folded up as shown in Figs. I and III.

Assuming the parts 1, 2 and 3, disconnected, 95 it will be readily understood that the nut 15 and spacer sleeves 16 are first removed, from the pivot component 3, whereupon said component is—for example—passed through the boring 17 in the right-hand front leg, with a 100

spacer 16 slipped thereon at the inside. Thereupon the step horses 9 are positioned between the stool front legs 5 with the holes 13 registering the borings 17, when the pivot 5 component 3 is passed therethrough, the second spacer sleeve 16 inserted between the left-hand horse 9 and proximate leg 5, whereupon the pivot component 3 is pushed through the boring 17 in said leg and the lock nut or nuts 10 15 applied.

When the convertible stool-steps is collapsed or folded, as shown by Figs. I and III it is adapted for use as a bench or stool in an obvious manner. Now, it will be readily 15 understood from Fig. III that the balanced step component 2 may be readily moved on the pivot 3 or overbalanced by a slight downwardly-curving pressure of a person's shoe heel 20 against the stretcher-bar or actuator 20 12. Or, in other words, when the steps 2 are rocked or over-balanced to the position indicated by dotted lines in Fig. III, said steps will "tumble" or fall by gravity to the position shown in Fig. II, without either lifting, 25 turning or disturbing the position of the stool 1, thereby providing a strong steps or short ladder.

The various parts may be made from wood, fiber, composition, hardened rubber, pressed 30 paper, and sheet metal wholly; or in part; or in varied combinations thereof, without departure from the essential features of the invention set forth.

Having thus described my invention I 35 claim:—

1. Convertible stool-steps comprising a stationary structure serviceable as a stool, a balanced steps foldable within the confines of said stool, a pivot member secured across 40 the stool affording bearing for the steps, and a stretcher-bar intermediate the side components of the steps and rearwardly of the pivot member, said stretcher-bar serving as an actuator to move the steps from the folded-in position to service location by a slight pedal pressure exerted against without disturbing the position of the stool portion aforesaid.

2. Convertible stool-steps comprising a 50 stationary stool including a top with front and back legs rigidly braced by appropriate horizontals, a balanced steps foldable within the confines of said stool, a pivot component secured between the stool front legs affording bearing for the steps, tubular spacers on the pivot component between the step risers and front legs, a stretcher-bar intermediate the step risers rearwardly adjacent the pivot member, said steps being adapted for folding within the confines of the stool and movement to stair relation by a downwardly-curving pedal pressure exerted against the stretcher-bar, and buffer stops on the rear horizontal of the stool.

3. Convertible stool-steps comprising a

rigid structure adapted for use as a stool, steps foldable within the confines of said stool, a pivot component secured between the stool front legs affording bearing for the steps, means preventing lateral movement of the steps relative to the stool, and a stretcher-bar intermediate the step risers rearwardly adjacent the pivot member; said stretcher-bar serving as an actuator to move the steps from within the confines of the stool to stair relation by a slight pressure exerted thereagainst. 70 75

4. Convertible stool-steps comprising a rigid structure adapted for use as a stool, a step portion foldable within the confines of said stool, pivot means for said step portion, stop means positioning said step portion when at rest within the stool with the greater portion of the weight of said step portion to one side of said pivot means and actuator means secured across said step portion and having at least a portion thereof lying to the opposite side of said pivot means from the side to which the weight of the step portion lies when the step portion is within the stool, whereby a slight downwardly-curving pressure on the actuator means lying to the said opposite side of the pivot point rotates the step portion from the stop means into service position outside the confines of the stool. 80 85 90

5. Convertible stool-steps comprising a 95 rigid structure serviceable as a stool, a step portion rotatable to a position within the stool, pivot means securing the step portion to the stool, said pivot means lying to one side of the step portion whereby the step portion 100 is maintained within the stool by gravitational action, and actuator means for rotating the step portion into service position, said actuator means being spaced laterally from the pivot means whereby a slight downwardly-curving pressure thereon rotates the step portion against gravitational action into service position. 105

In testimony whereof, I have hereunto signed my name at Lititz, Pennsylvania, this 110 19th day of August, 1929.

ELMER B. BECK.
